UNITED STATES PATENT OFFICE

JOSEPH SZECHENYI, OF CHICAGO, ILLINOIS

DESIGN FOR A FACE PLATE FOR AN AUTOMOBILE LIGHT OR LAMP

Application filed February 19, 1931. Serial No. 38,722. Term of patent 3½ years.

To all whom it may concern:

Be it known that I, JOSEPH SZECHENYI, a citizen of Yugoslavia, residing at Chicago, in the county of Cook and State of Illinois, have invented a new, original, and ornamental Design for a Face Plate for an Automobile Light or Lamp, of which the following is a specification, reference being had to the accompanying drawings, forming part thereof.

I claim:

The ornamental design for a face plate for an automobile light or lamp, as shown.

JOSEPH SZECHENYI.
